(57) CLAIM

The ornamental design for a fuel tank as shown and described.

DESCRIPTION

The file of this patent contains at least one drawing/photograph executed in color. Copies of this patent with color drawing(s)/photograph(s) will be 13 provided by the Office upon request and payment of the 19 necessary fee.

FIG. 1 is a top-front-right side perspective view of a fuel tank embodying my new design;

FIG. 2 is a top-front perspective view thereof;

FIG. 3 is a front-left side perspective view thereof;

FIG. 4 is a top-front-left side perspective view thereof;

FIG. 5 is a top-left side perspective view thereof;

FIG. 6 is a top-rear-left side perspective view thereof;

FIG. 7 is a rear-left side perspective view thereof;

FIG. 8 is a rear-right side perspective view thereof;

FIG. 9 is a top-rear-right side perspective view thereof;

FIG. 10 is a top-right side perspective view thereof;

FIG. 11 is a bottom-front-right side perspective view thereof;

FIG. 12 is a top-rear perspective view thereof;

FIG. 13 is a bottom-front-left side perspective view thereof;

FIG. 14 is a bottom-left side perspective view thereof;

FIG. 15 is a bottom-rear-left side perspective view thereof;

FIG. 16 is a bottom-rear perspective view thereof;

FIG. 17 is a bottom-rear-right side perspective view thereof;

FIG. 18 is a bottom-right side perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof; and,

FIG. 24 is a bottom plan view thereof.
